UNITED STATES PATENT OFFICE.

DANIEL F. LEPLEY, OF CONNELLSVILLE, PENNSYLVANIA.

VENTILATING FAN-WHEEL.

1,150,278.

Specification of Letters Patent. Patented Aug. 17, 1915.

Application filed September 18, 1914. Serial No. 862,393.

To all whom it may concern:

Be it known that I, DANIEL F. LEPLEY, a citizen of the United States, residing at Connellsburg, in the county of Fayette and State of Pennsylvania, have invented a new and useful Ventilating Fan-Wheel, of which the following is a specification.

The present invention relates to improvements in ventilating fan wheels, one object 10 of the invention being the provision of a divisional disk of a double ventilating fan wheel that increases the efficiency of the fan wheel in that it prevents the productions of eddies due to high winds and the like that 15 usually tend to prevent the maximum passage of air between the blades when the wind is blowing from one side and is deflected by the divisional disk.

In constructing fan wheels of this character, it is generally the practice to use a solid 20 divisional disk of substantially the full diameter of the wheel, thus dividing the wheel into practically two wheels, in which the respective operating sides or blades are isolated from one another. It has been found in practise, that when the wind is blowing from one side and is deflected by the divisional disk, that not only the maximum efficiency of the side against which the wind 25 is directed is affected, but the blades upon the opposite side of the disk are also affected, thus preventing the fan from operating to produce the desired result. To overcome this defect, it has been found that by 30 reducing the diameter of the divisional disk, so that the periphery thereof is within the inner edge of the outer supporting rings of the fan wheel to produce a concentric space adjacent the intermediate edges of the blades 35 or entirely between the blades at said intermediate portion, that the currents of air due to the wind engaging either side of the divisional disk, will rather assist than retard the proper action of the blades in producing 40 the desired ventilating effect.

With the foregoing and other objects in view which will appear as the description proceeds, the invention resides in the combination and arrangement of parts and in 45 the details of construction hereinafter described and claimed, it being understood that changes in the precise embodiment of the invention herein disclosed can be made within the scope of what is claimed without departing from the spirit of the invention.

In the drawings—Figure 1 is a view show-

ing one half of the ventilating fan wheel in side elevation and the other half in section. Fig. 2 is a view illustrating a portion of the fan wheel in end elevation and the lower 60 portion in section.

Referring to the drawings, the numeral 1 designates the sectional shaft engaging members of the fan wheel, which in large wheels is made in two sections so that the wheel 65 may be transported in two parts for assemblage.

The main spokes 4 are carried by the member 1, while a sectional disk member 3 is disposed upon the shaft (not shown) intermediate of the members 1, to support the divisional disk or partition 11, to which is attached the radial plates 2.

Connected to the outer ends of the plates 2, are the annular members or rims 5 which 70 constitute the main outer rim of the wheel. Connected to the spoke 4 and of lesser width than the rims 5, is the partitional rim 6, which divides the blade space between the rims 5, in two spaces, as usual. Two sets 80 of blades are consequently employed, and as shown, three distinct constructions of blades are preferably employed. These blades are clearly illustrated in Fig. 1, in which the longer blades 7 are so constructed 85 that their inner ends are at a tangent to and within the periphery of the partitional disk 11 while the inner ends of the blades 8 are at a slightly less angle than the blades 7 and terminate at a point substantially at the 90 periphery of the disk 11. The blades 9 are between the rims 5 and are substantially the length of the width thereof.

It will be noted that the partitional disk 11 is of a diameter less than the internal 95 diameter of the outer rims 5, therefore providing between its periphery and the inner diameter of the partitional ring 6, the concentric opening 12, thereby providing the passageway for the undue draft or wind blown against either side of the disk 11 so that the same is not deflected to interfere with the efficiency of the blades at the wind side of the disk 11 and at the same time provides a passage so that the currents of air are permitted to pass therebeyond and be properly deflected through the blades at the opposite side of the disk without interfering with the efficiency thereof. It has also been found that the ring or band 6 may be 100 dispensed with, thus providing a clear open space beyond the periphery of the parti-

tional disk 11, it being essential, however, that the periphery of the disk 11 terminate at a point within the internal diameter of the rings 5.

5 What is claimed is:

1. A ventilating fan wheel, including a supporting structure, a plurality of blades, and a partitional disk carried by the structure and having its periphery terminating at 10 a point within the blade supporting portion thereof.
2. A ventilating fan wheel, including a hub, two annular rims carried by the hub and constituting a blade support, and a partitional disk carried by the hub and having its periphery terminating at a point within the inner diameter of the annular blade supporting members.
3. A ventilating fan wheel, including a 20 hub, spokes carried thereby, two annular members carried by the spokes, a plurality of blades supported between the annular members, and a partitional disk carried by the hub intermediate of its ends and having 25 its periphery disposed in spaced relation to the inner diameters of the annular members.
4. A ventilating fan wheel, including a hub, spokes carried thereby, two annular members carried by the spokes, a plurality 30 of blades supported between the annular members, a partitional disk carried by the hub intermediate of its ends and having its periphery disposed in spaced relation to the

inner diameters of the annular members, and an annular blade partitioning member 35 carried between the annular members and the blades and circumferentially alined but spaced from the partitional disk.

5. A ventilating fan wheel, including a hub, a plurality of spokes carried thereby, 40 two flat rings attached to the spokes at opposite sides, a plurality of blades disposed between the flat bands, and a partitional disk carried by the hub intermediate of its ends, said partitional disk having its periphery of lesser diameter than the inner 45 diameter of the rings.

6. A ventilating fan wheel, including a hub, a plurality of spokes carried thereby, 50 two flat rings attached to the spokes at opposite sides, a plurality of blades disposed between the flat rings, a partitional disk carried by the hub intermediate of its ends, said partitional disk having its periphery of lesser diameter than the inner 55 diameter of the rings, and a partitional ring disposed between the blade supporting rings and in circumferential alinement but spaced from the periphery of the partitional disk.

In testimony that I claim the foregoing 60 as my own, I have hereto affixed my signature in the presence of two witnesses:

DANIEL F. LEPLEY.
